UNITED STATES PATENT OFFICE.

MICHAEL J. NASH, OF ST. LOUIS, MISSOURI, ASSIGNOR TO NATIONAL BISCUIT COMPANY, OF JERSEY CITY, NEW JERSEY, AND CHICAGO, ILLINOIS, A CORPORATION OF NEW JERSEY.

CAN FOR BAKERY OR SIMILAR PRODUCTS.

SPECIFICATION forming part of Letters Patent No. 714,393, dated November 25, 1902.

Application filed July 5, 1902. Serial No. 114,480. (No model.)

To all whom it may concern:

Be it known that I, MICHAEL J. NASH, a citizen of the United States, residing at the city of St. Louis, in the State of Missouri, have 5 invented certain new and useful Improvements in Cans for Bakery and Similar Products, of which the following is a specification.

Crackers, biscuit, fancy cakes, and other similar bakery products have heretofore been 10 sold to the retail trade in rectangular tin boxes containing a hinged cover, a glass front, and a removable slide parallel with and a slight distance behind the glass front of the can, the purpose of this slide being to enable 15 the goods contained within the can to be displayed and represented by a sample of the same goods neatly packed in the narrow space between the glass front and the slide, the object of this being to give the can the appearance 20 at all times of being full and also to make known the character of the contents by a simple glance at the glass front. Heretofore these slides have been made of tin, and experience has shown that in a great majority 25 of instances where goods are sold to the retail trade in such cans, which cans are returnable when empty to the baker, the tin slides are usually removed by the persons to whom these returnable cans are delivered and are used 30 for other purposes, thus entailing a very considerable loss upon the owner of the cans.

The principal object of my invention is to equip a can of this character with a removable slide which shall possess every advantage of the tin slide in respect to serviceability and appearance and yet shall be producible at such a slight cost that its abstraction from the cans will not mean any serious loss or inconvenience to the owner.

40 A further object of the invention is to produce a slide of practically no use outside of or beyond its special function in connection with the can, thus removing the temptation on the part of the users of the can to abstract 45 the slide for other purposes.

To these and other ends my invention resides, primarily, in a novel material and construction of removable slide for cans and boxes of the character specified.

50 My invention further consists in a can or

box of this character in combination with my new and improved slide and means whereby the latter may be efficiently held therein with capacity for ready insertion and withdrawal.

My invention is illustrated in the accompanying drawings, wherein—

Figure 1 is a perspective view of a tin can or box embodying my invention, the same being shown as closed and having its false front filled with display goods. Fig. 2 is a top plan 60 view of the front portion of the can with the cover removed, illustrating the false front and the slide and its retaining means whereby the false front is created. Fig. 3 is a front elevational view of the slide withdrawn from 65 the can. Fig. 4 is an edge view of the same; and Fig. 5 is an enlarged detail perspective view of the upper left-hand corner of the slide, illustrating the manner in which the tin binding is attached and secured to the pasteboard 70 body of the slide.

Referring to the drawings, 6 designates as an entirety a rectangular tin can or box of the variety wherein crackers, cakes, and other bakery products are ordinarily sold by the 75 manufacturers to the retail dealers, these being ordinarily the property of the baker or manufacturer and returnable to him when empty. The can is provided with a hinged cover or top 7, provided with a latch 8, and 80 the front wall of the can usually has either a solid glass front or is provided with a sizable aperture, such as the circular opening herein shown at 9, which is backed by a glass or other transparent closure 10, Fig. 2. 85

A slight distance, usually about one and one-half inches, in rear of the glass front 10 and parallel therewith is provided a removable slide, (designated in Fig. 2 as an entirety by 11.) This slide has heretofore consisted 90 usually of a simple rectangular sheet of tin, the side edges of which have engaged retaining devices or guides on the inner faces of the side walls of the can. In view of the fact that the gist of my present invention resides 95 in the materials and construction of this slide I will describe the same with some particularity.

In carrying out my invention I take a piece of heavy pasteboard or board made from 100

wood-pulp or other similar flexible material and cut the same to a width slightly less than the width of the can and to a height slightly greater than the height of the can. This 5 board constitutes the body of the slide and is designated in Figs. 3 to 5 by the numeral 11^a. I then bend over the upper and lower margins of this board, as indicated at 11^b in Fig. 5, so that said margins lie parallel with 10 the main body of the board. I then take a strip of tin or other readily-pliable sheet metal 12, bending the same longitudinally thereof along two lines, thus forming two overlying parallel sides 12^a and 12^b and an inwardly-extending 15 marginal flange 12^c, which lies between the inner portions of the side walls 12^a and 12^b of the binding-strip. This binding-strip thus formed is applied to both the top and bottom margins of the slide, and in 20 applying the same the flange 12^c engages behind the lower portion of the inwardly-bent marginal portion 11^b of the pasteboard slide-body, while the exposed side walls 12^b and 12^a of the binding-strip respectively overlie 25 and engage the outer faces of the marginal portion 11^b and the adjacent upper and lower portions of the slide-body. When the parts are engaged in the manner described, they are very securely united by simply pressing 30 together the two sides of the tin binding-strip.

To the inner side walls of the can are secured at the proper distance from the front wall vertical grooved guides or slideways 13, 35 each of which may conveniently be formed by bending a strip of tin centrally lengthwise into U shape and soldering or otherwise attaching the same to the inner face of the side wall of the can. These guides are of a 40 width sufficient to receive the end portions of the binding-strips 12, as well as the side portions of the body 11^a of the slide. The slide is inserted in these vertical guides with its unbound side margins and the end portions 45 of its bound margins engaged thereby, while its top and bottom margins are stiffened by the binding-strips 12, already described, and it will thus be seen that when

the slide is in place it is, in effect, provided with a metallic binding on all foursides thereof, thus lending to the same the required degree of rigidity to form the back wall of the false front 14, within which the crackers or other goods (indicated at 15) are placed for display through the glass front 10. 55

A mere rectangular sheet of pasteboard or the like would hardly of itself possess the necessary strength and rigidity to serve satisfactorily in the situation described, although in the case of a can containing very light 60 goods it might answer; but by providing the same with a cheap form of stiffening in the nature of a sheet-metal binding I render the same an entirely efficient and highly economical substitute for the solid tin slides 65 heretofore used.

Although I have described my preferred manner of applying the sheet-metal binding to the top and bottom margins of the slide, yet my invention is not limited, except to the 70 extent hereinafter indicated in the claims, to the means and manner herein shown of securing said binding to the slide.

I claim—

1. A slide for cans of the character described, comprising a rectangular sheet of heavy pasteboard or the like, and having its upper and lower margins bent inwardly, and longitudinally-folded sheet-metal binding-strips interlocked with said inwardly-bent 75 margins of the slide, substantially as described.

2. The combination with a can of the character described, provided with vertical slides on the inner surfaces of its side walls near 85 the front of the box, of a slide therefor comprising a rectangular sheet of heavy pasteboard or the like adapted to engage said guides along its side margins and having its top and bottom margins provided with sheet-metal binding-strips secured thereto, substantially as described. 90

MICHAEL J. NASH.
